UNITED STATES PATENT OFFICE.

JOSEPH BENOSCH, OF AMSTERDAM, NEW YORK, ASSIGNOR TO KLAUDER-WELDON
DYEING MACHINE COMPANY, OF AMSTERDAM, NEW YORK, A CORPORATION OF
NEW YORK.

DYEING-MACHINE.

1,120,646.

Specification of Letters Patent.

Patented Dec. 8, 1914.

Application filed March 9, 1914. Serial No. 823,495.

To all whom it may concern:

Be it known that I, JOSEPH BENOSCH, a citizen of the United States, residing at Amsterdam, in the county of Montgomery and State of New York, have invented certain new and useful Improvements in Dyeing-Machines, of which the following is a full, clear, and exact description, such as will enable others skilled in the art to which it applies to make and use the same.

This invention relates to dyeing and scouring machines, and with respect to certain more specific features thereof, to so-called rotary skein machines.

The invention has for one of its objects to provide a simple, practical and durable machine of the character above referred to.

Another of the objects of the invention is to provide reliable and effective mechanism for rotating the skein-carrying members or yarn-sticks.

Another object of the invention is the provision of improved means for "tripping" the skein-carrying members, which will embody features of safety and reduction of wear on the parts, and which, by simple adjustment or manipulation of parts, may be rendered suitable for use on either side of a so-called "double machine" or on single machines of different rotative directions.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the drawings, in which is shown one of various possible embodiments of this invention, Figure 1 is a front elevational view of a dyeing machine of the "double type;" Figs. 2 and 3 are, respectively, a plan view and a front elevational view of an improved form of detent; Figs. 4, 5, 6 and 7 are diagrammatic views introduced to demonstrate the operation of the detent; Fig. 8 is a perspective view of the support for the pawl or trip carrier; and Fig. 9 is a perspective view of a modification.

Referring now to the drawings, in which like characters of reference refer to similar parts throughout the different views, the

numeral 1 indicates a dye vat or housing comprising side walls 2 and 3 and a roof 4. A driving shaft 5 is mounted to rotate in the housing 1 and is provided with a driving member 6. Upon the shaft 5 is mounted for rotation therewith a yarn-stick-supporting frame 7 comprising a central spider 8 and outside spiders 9 and 10 co-operatively associated, and secured on said shaft against rotary displacement. The spiders 8, 9 and 10 are preferably ring-shaped and provided with recesses to receive, respectively, cups or sockets 11, 12 and 13. The sockets 12 and 13 are mounted for rotary movement in the recesses provided in the spiders 9 and 10, respectively, and the cups or sockets 11 may be fixed or movable in the recesses provided in the spider 8, as desired. Outer yarn-sticks 14 and 15 are supported, respectively, between the sockets 11 and 12 and the sockets 11 and 13, and the ends of said yarn-sticks which co-operate with the sockets 12 and 13 are provided with angular faces adapted to be held between corresponding angular faces of a recess 16 in each of said sockets. Inner yarn-sticks 17 and 18 are secured in any suitable manner between the spider 8 and the outside spiders 9 and 10. The yarn-sticks 14 and 15 are preferably disposed in longitudinal alinement, and the yarn-sticks 17 and 18 are preferably correspondingly arranged. When the machine is in operation dyeing yarn, a considerable number of skeins of yarn are supported over each outer yarn-stick and its co-operating inner yarn-stick. It is of course understood that the yarn-stick-supporting frame carries a plurality of outer yarn-sticks between each pair of spiders. For instance, there might be supported between the spider 8 and the spider 10 twenty-five or thirty yarn-sticks similar to the one indicated at 15 and supported in a similar manner, and, of course, each one of these twenty-five or thirty outer yarn-sticks has its co-operating inner yarn-stick. Fixed to the side walls 2 and 3 of the casing 1 are detents 19 and 20, similar in construction and only one of which will be hereinafter described. Star wheels 21 and 22 are, respectively, associated with the sockets 12 and 13 and adapted to move therewith, and it is by reason of the engagement of the star wheels 21 and 22 with the detents 19 and 20, respec-

tively, that relative movement is imparted to the yarn-sticks 14 and 15 in the yarn-stick-supporting frame 7.

In machines of the general character of the one set forth in the drawings, a vat is provided at the bottom portion thereof, and the yarn supported on the various sets of yarn-sticks passes through a dye contained in said vat, in the path of travel of the frame 7. It will be obvious that the yarn in contact with these supporting yarn-sticks is not readily accessible to the dyeing material, and in order to obtain a uniform dyeing of the yarn it has been found desirable to slightly rotate the yarn-sticks in order to bring portions of the yarn which were in contact with the sticks as they passed through the dyeing material on one revolution to be presented to the dyeing material on the next succeeding revolution out of contact with said sticks. Accordingly, it is an object of this invention to provide improved means for causing movement of the yarn-sticks relative to the yarn-stick-supporting frame. The detent 19 comprises a support 23 secured to the side wall 3 of the casing by means of bolts 24. Slots 25 are provided in order to permit vertical adjustment of said support on the wall 3. Pivotally mounted on an inwardly-extending lug portion 26 of the support 23 is a trip carrier 27. This carrier comprises a lever 28 having an upright portion 29 adapted to serve as a bearing and support for a movable trip 30. The trip carrier 27 also comprises a stop 28', preferably integral therewith, which serves to limit the movement of the trip 30. A stud bolt 31 secures an arm 32 of the trip 30 to the upstanding portion 29 of the trip carrier 27 and the trip 30 is freely pivotally movable about said stud except as it engages the stop 28 on one side or the other of said stop. The trip carrier 27 and its appurtenances are adjustable toward and away from the path of the star wheel 21 by means of a stud pivot bolt 33 which is adapted to be secured in different positions relative to a slot 34 formed in the lug 26 of the support 23. It will, therefore, be seen that the trip 30 may be adjusted vertically by adjusting the support 23 in that direction, and that the trip 30 may be adjusted toward and away from the side wall of the casing by adjusting the stud pivot bolt 33 in the slot 34. At the outer end of the lever 28 of the trip carrier there is attached one end of a spring 35, the opposite end of which is attached to a pin 36 connecting with the side wall of the casing. The support 23 has associated therewith means adapted to limit the action of this spring 35, and said means preferably comprise upstanding lugs 37 and 38. It will be obvious that only one of these lugs is used when the device is in operation, but it is found con-

venient to construct the support with both lugs and to remove the lug which is not to be used. If desired, the lugs 37 and 38 may be weakened, as indicated at 39, to facilitate the removal thereof when the device is being assembled. The invention, of course, contemplates the use of adjustable stops in place of these removable stops, as clearly indicated in Fig. 9 of the drawings, in which the numeral 42 indicates an adjustable plate disposed between the support 23 and the trip carrier. The plate 42 is reversible and has an elbow 43 which may be moved to abut either of the shoulders 44 formed in the support. When the pivot stud 33 is in place the plate is locked against rotative movement by reason of the elbow 43 bearing against one of the shoulders 44. Stops 45 are provided on said plate and perform the function of the stops shown in Fig. 8 at 37 and 38.

Referring now to Figs. 2, 3 and 8, it will be seen that stop 28 will limit the movement of the trip 30 about the pivot 31 and that stop 38 having been removed, the trip carrier 27 is freely movable about pivot 33 against the action of the spring 35, and it will be seen further that the stop 37 will limit the movement of the trip carrier against the action of the said spring. 95

In the operation of this apparatus the support 23 being secured to the side wall 3 of the casing presents the trip 30 directly in the path of travel of one of the fingers of each star wheel 21 carried by the spider 9, 100 and as the frame 7 moves to carry the star wheels successively into engagement with the trip, the star wheels are caused to rotate say, for instance, a quarter of a turn, and acting through the socket 12 they turn 105 the yarn-sticks 14 accordingly.

Fig. 5 of the drawings shows the trip 30 in proper relation to the stop 28 to normally cause rotation of the star wheel as it proceeds with its spider in the direction indicated by the arrow. Fig. 6 of the drawings represents a spider moved slightly farther in the same direction, the star wheel having been actuated. Fig. 4 exemplifies the action of the trip as the frame moves in the 110 opposite direction. Under certain conditions the yarn-sticks may offer a very considerable resistance to the turning mechanism, as, for example, when the skeins of yarn become tangled and tend to hold the sticks against relative movement. The action of the detent under these conditions is exemplified in Fig. 7 of the drawings, wherein the trip carrier is shown as yielding against the action of its spring, the same 115 continuing to yield until forced by the then non-rotatable star wheel out of the path of travel of said star wheel. It will be obvious that the spring will return the parts to their normal position against the stop 37 immedi- 120

ately the star wheel passes out of engagement with the trip. In the event that it should be desired to dye the yarn by rotating the frame in an opposite direction, the 5 parts of this device can be readily adjusted to an operative relation with the star wheels similar in effect to that which they bore as the frame traveled in its regular direction of movement. Or it will be clear that the device 10 is reversible in character, and may be used on either side of a double machine, as has been described, and as is shown in Fig. 1 of the drawings. All that is necessary to render the detent applicable to one or the 15 other of the two side walls of the casing in tripping relation with the star wheels is the removal or adjustment of one of the stops 37 and 38 and a movement of the trip 30 into proper relation with the stop 28, the spring 20 35, of course, being changed to exert its influence in the opposite direction. By using a trip of this character, the necessity of providing so-called right and left detents is obviated, accordingly relieving the apparatus 25 of the expense consequent upon having to provide detents of different shapes to accommodate the above set forth situations. All of the sockets which are associated directly with the star wheels are provided 30 with ratchet wheels 40 which coöperate with pawls 41 pivotally mounted on the frame to hold the yarn-sticks against retreat after the same have been turned by the detent. The trip 30 is forked at its lower free end 35 and straddles a roll 46 mounted on a pivot pin 47 for rolling contact with the fingers of the star wheels, thereby avoiding a great degree of friction and minimizing the amount of wear on the parts.

40 It will be seen from the foregoing that an apparatus is provided which is extremely simple and inexpensive to manufacture, and which accomplishes, among others, the objects hereinbefore set forth.

45 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I 55 claim as new and desire to secure by Letters Patent is:

1. In dyeing apparatus or the like, in combination, a movable yarn-stick-supporting frame, means carried by said frame combination, a movable yarn-stick-supporting 60 to be actuated to cause movement of the yarn-sticks relatively to said frame, means adapted operatively to engage said member in one direction of movement of said 65 frame and permit said member to move

freely by as the frame moves in an opposite direction, and means whereby the action of said last means may be reversed to permit said member to move freely by as the frame moves in said one direction and 70 operatively to engage said member as the frame moves in said opposite direction.

2. In dyeing apparatus or the like, in combination, a movable yarn-stick-supporting frame, means carried by said frame comprising a projecting member adapted to be actuated to cause movement of the yarn-sticks relatively to said frame, means adapted operatively to engage said member yielding 75 in one direction of movement of said frame and permit said member to move freely by as the frame moves in an opposite direction, and means whereby the action of said last means may be reversed to permit said member to move freely by as the frame 80 moves in said one direction and operatively to engage said member as the frame moves in said opposite direction.

3. In dyeing apparatus or the like, in combination, a movable yarn-stick-supporting frame, a support for a detent fixed relative to said frame, means carried by said frame adapted to be actuated to cause movement of the yarn-sticks relatively to said frame, a detent secured to said support comprising means adapted to actuate said last means as the frame moves in one direction and to yield without actuating said last means as the frame moves in the opposite direction, means whereby the action of said 90 actuating means may be reversed to permit movement of said frame in said one direction without actuating said means, and to cause actuation of said means in the opposite direction of movement of the frame, and 95 means adapted to yield under an increased pressure to permit said actuating means to move out of the path of travel of said means carried by said frame.

4. In dyeing apparatus or the like, a 100 stick, means adapted to translate said stick, a trip, means whereby translation of said stick past said trip causes said stick to rotate, and means whereby said trip may be set to coöperate with the second-mentioned 105 means in either of opposite directions of translation of said stick.

5. In dyeing apparatus or the like, in combination, a movable yarn-stick-supporting frame, means carried thereby adapted to 110 receive yarn-sticks and comprising a star wheel, a stationary support for a detent, and a detent comprising a stop having opposite sides and a trip adapted to coact respectively with one or the other of said opposite 115 sides to offer resistance to said star wheel as it moves against said pawl in either of opposite directions.

6. In dyeing apparatus or the like, in combination, a movable yarn-stick-supporting 120

frame, means carried thereby adapted to receive yarn-sticks and comprising a star wheel, a stationary support for a detent, and a detent comprising a yielding stop having 5 opposite sides and a trip adapted to coact respectively with one or the other of said opposite sides to offer resistance to said star wheel as it moves against said trip in either of opposite directions, said stop being yielding 10 in character to permit said star wheel to move said trip out of engagement therewith under certain conditions.

7. In dyeing apparatus or the like, in combination, a movable yarn-stick-supporting 15 frame, means carried thereby adapted to receive yarn-sticks and comprising a star wheel, a stationary support for a detent, and a detent comprising a stop having opposite sides and a trip adapted to coact with one 20 side of said stop to offer resistance to said star wheel as the latter moves thereagainst in one direction and to yield as said star wheel moves thereagainst in the opposite direction, said trip being adapted to coact 25 with the other side of said stop to reverse the action of said trip.

8. In dyeing apparatus or the like, in combination, a movable yarn-stick-supporting frame, means carried thereby adapted to receive 30 yarn-sticks and comprising a star wheel, a stationary support for a detent, and a detent comprising a yielding stop having opposite sides and a trip adapted to coact with one side of said stop to offer resistance to said star wheel as the latter moves thereagainst in one direction and to yield as said star wheel moves thereagainst in the opposite direction, said trip being adapted to coact with the other side of said 35 stop to reverse the action of said trip, said stop being yielding in character to permit said star wheel to move said trip out of engagement therewith under certain conditions.

45 9. In dyeing apparatus or the like, in combination, a movable yarn-stick-supporting frame, means carried thereby adapted to receive yarn-sticks and comprising a star wheel, a stationary support for a detent, and 50 a detent comprising a stop having opposite sides and a trip adapted to coact with one side of said stop to offer resistance to said star wheel as the latter moves thereagainst in one direction and to yield as said star 55 wheel moves thereagainst in the opposite direction, said trip being pivotally movable to coact with the other side of said stop to reverse said conditions.

10. In dyeing apparatus or the like, in 60 combination, a movable yarn-stick-supporting frame, means carried thereby adapted to receive yarn-sticks and comprising a star wheel, a stationary support for a detent, and a detent comprising a yielding stop having 65 opposite sides and a trip adapted to coact

with one side of said stop to offer resistance to said star wheel as the latter moves thereagainst in one direction and to yield as said star wheel moves thereagainst in the opposite direction, said trip being pivotally movable 70 to coact with the other side of said stop to reverse the action of said trip, said stop being yielding in character to permit said star wheel to move said trip out of engagement therewith under certain conditions. 75

11. In dyeing apparatus or the like, in combination, a fixed support for a detent, a detent mounted thereon comprising a stop member, a trip adapted to coact with said stop member to offer resistance to a member 80 moving against said trip in one direction and to yield to permit the member to move freely by said trip in the opposite direction, and means whereby said trip is adapted to coact with said stop member to reverse 85 the action of said trip.

12. In dyeing apparatus or the like, in combination, a fixed support for a detent, a detent mounted thereon comprising a stop member, a trip adapted to coact with said 90 stop member to offer resistance to a member moving against said trip in one direction and to yield to permit the member to move freely by said trip in the opposite direction, and means whereby said trip may be moved 95 to coact with said stop to reverse the action of said trip.

13. In dyeing apparatus or the like, in combination, a fixed support for a detent, and a detent mounted thereon comprising a 100 stop member and a trip pivotally mounted relatively to said stop member and adapted to coact with one side of said stop member to offer resistance to a member moving against said trip in one direction and to 105 yield to permit the member to move freely by said trip in the opposite direction, said trip being pivotally movable into coacting relation with the opposite side of said stop to reverse the action of said trip. 110

14. In dyeing apparatus or the like, in combination, a support, means secured to said support adapted to carry a movable trip, means adapted to resist the movement of said trip in one direction and permit it 115 to be moved freely in the opposite direction, and means whereby the relative positions of said trip and said resisting means may be changed to permit said trip to be moved 120 freely in said one direction and to resist movement thereof in said opposite direction.

15. In dyeing apparatus or the like, in combination, a support, means secured to said support adapted to carry a movable trip, means adapted to resist yieldingly the movement of said trip in one direction and permit it to be moved freely in the opposite direction, and means whereby the relative positions of said trip and said resisting means may be changed to permit said trip 125 130

to be moved freely in said one direction and to resist yielding movement thereof in said opposite direction.

16. In dyeing apparatus or the like, in combination, a support, means secured to said support adapted to carry a movable trip, spring-controlled means adapted to resist the movement of said trip in one direction and permit it to be moved freely in the opposite direction, and means whereby the relative positions of said trip and said resisting means may be changed to permit said trip to be moved freely in said one direction and to resist movement thereof in said opposite direction.

17. In dyeing apparatus or the like, in combination, a support, means movably secured to said support adapted to carry a movable trip, means adapted to position said trip-carrying means, means adapted to resist the movement of said trip in one direction and permit it to be moved freely in the opposite direction, and means whereby the relative positions of said trip and said resisting means may be changed to permit said trip to be moved freely in said one direction and to resist movement thereof in said opposite direction.

18. In dyeing apparatus or the like, in combination, a support, means movably secured to said support adapted to carry a movable trip, means adapted to position said trip-carrying means comprising a spring acting to move said trip-carrying means outwardly from said support and a stop to limit the movement thereof, means adapted to resist the movement of said trip in one direction and permit it to be moved freely in the opposite direction, and means whereby the relative positions of said trip and said resisting means may be changed to permit said trip to be moved freely in said one direction and to resist movement thereof in said opposite direction.

19. In dyeing apparatus or the like, in combination, a support, a trip carrier pivotally secured thereto to swing about a vertical axis, a trip pivotally secured to said carrier to swing about a horizontal axis, spring means normally acting on said carrier to move said trip into the path of travel of a member to be actuated, said trip and said spring means being on opposite sides of said vertical axis, a stop movable with said carrier adapted to resist the movement of said trip in one direction and permit it to be moved freely in the opposite direction, and means whereby the relation of said trip and said stop may be changed to cause said stop to resist movement in said opposite direction and permit movement in said one direction.

20. In dyeing apparatus or the like, in combination, a support, a trip carrier pivotally secured thereto to swing about a vertical

axis, a trip pivotally secured to said carrier to swing about a horizontal axis, spring means normally acting on said carrier to move said trip into the path of travel of a member to be actuated, said trip and said spring means being on opposite sides of said vertical axis, a stop movable with said carrier adapted to resist the movement of said trip in one direction and permit it to be moved freely in the opposite direction, and means whereby said trip may be moved about said horizontal axis into engagement with an opposite side of said stop to cause said stop to resist movement in said opposite direction and permit movement in said one direction.

21. In dyeing apparatus or the like, in combination, a support, a trip carrier pivotally secured thereto to swing about a vertical axis, a trip pivotally secured to said carrier to swing about a horizontal axis, spring means normally acting on said carrier to move said trip into the path of travel of a member to be actuated, said trip and said spring means being on opposite sides of said vertical axis, a stop movable with said carrier adapted to resist the movement of said trip in one direction and permit it to be moved freely in the opposite direction, means whereby the relation of said trip and said stop may be changed to cause said stop to resist movement in said opposite direction and permit movement in said one direction, and means whereby said trip-carrier may be swung out of the path of travel of the member to be actuated against the action of said spring means.

22. In dyeing apparatus or the like, in combination, a support, a trip carrier pivotally secured thereto to swing about a vertical axis, a trip pivotally secured to said carrier to swing about a horizontal axis, spring means normally acting on said carrier to move said trip into the path of travel of a member to be actuated, said trip and said spring means being on opposite sides of said vertical axis, a stop movable with said carrier adapted to resist the movement of said trip in one direction and permit it to be moved freely in the opposite direction, and stop means associated with said support and adapted to limit the movement of said carrier in either direction of its movement about said vertical axis.

23. In dyeing apparatus or the like, in combination, a vertically adjustable support, a trip carrier pivotally secured thereto to swing about a vertical axis and transversely adjustable therewith, a trip pivotally secured to said carrier to swing about a horizontal axis, spring means normally acting on said carrier to move said trip into the path of travel of a member to be actuated, said trip and said spring means being on opposite sides of said vertical axis, a

stop movable with said carrier adapted to resist the movement of said trip in one direction and permit it to be moved freely in the opposite direction, and means whereby the relation of said trip and said stop may be changed to cause said stop to resist movement in said opposite direction and permit movement in said one direction.

24. In dyeing apparatus or the like, in combination, a vertically adjustable support, a trip carrier pivotally secured thereto to swing about a vertical axis and transversely adjustable therewith, a trip pivotally secured to said carrier to swing about a horizontal axis, spring means normally acting on said carrier to move said trip into the path of travel of a member to be actuated, said trip and said spring means being on opposite sides of said vertical axis, a stop movable with said carrier adapted to resist the movement of said trip in one direction and permit it to be moved freely in the opposite direction, means whereby the relation of said trip and said stop may be changed to cause said stop to resist movement in said opposite direction and permit movement in said one direction, and means whereby said trip carrier may be swung out of the path of travel of the member to be actuated against the action of said spring means.

25. In dyeing apparatus or the like, in combination, a support for a trip carrier, a trip carrier movable thereon, and removable means associated with said support adapted to limit the movement of said carrier.

26. In dyeing apparatus or the like, in combination, a support for a trip carrier, a trip carrier movable thereon, and removable

means associated with said support adapted to limit the movement of said carrier in either direction.

27. In dyeing apparatus or the like, in combination, a support for a trip carrier, a spring-controlled trip carrier movable thereon, and removable means associated with said support adapted to limit the movement of said carrier.

28. In dyeing apparatus or the like, in combination, a support for a trip carrier, a trip carrier movable thereon, and removable means associated with said support adapted to limit the movement of said carrier, said means comprising stops removable at the will of the operator.

29. In dyeing apparatus or the like, in combination, a support for a trip carrier, a trip carrier movable thereon, and removable means associated with said support adapted to limit the movement of said carrier, said means comprising a pair of removable stops either of which is removable at the will of the operator.

30. In dyeing apparatus or the like, in combination, a yarn-stick-supporting frame comprising a central stick-supporting member and outside stick-supporting members, supporting means for detents fixed adjacent said outside members, and a reversible detent changeable to coöperate with the supporting means adjacent either outside member to offer resistance to pressure in one direction of rotation of said frame.

In testimony whereof I affix my signature, in the presence of two witnesses.

JOSEPH BENOSCH.

Correction in Letters Patent No. 1,120,646.

It is hereby certified that in Letters Patent No. 1,120,646, granted December 8, 1914, upon the application of Joseph Benosch, of Amsterdam, New York, for an improvement in "Dyeing-Machines," an error appears in the printed specification requiring correction as follows: Page 3, strike out lines 60, and insert the words *comprising a projecting member adapted*; and that the said Letters Patent should be read with this correction therein that the same may conform to the record of the case in the Patent Office.

Signed and sealed this 5th day of January A. D., 1915.

[SEAL.]

R. F. WHITEHEAD,
Acting Commissioner of Patents.
